(54) **STOVE PIPE, MANUFACTURING**

(76) Inventor: **John Colby**

John Catty

Letter Patent

To Whom it shall be given. John Catty, and making part of the same a certificate of description in the words, he and John Catty, inventors of his invention in the manufacturing of Steel pipes.

I begin with his parallel rollers with guides at each end of them, so that you would project a head and iron arms, extending from each end of the roller, so that you suppose the inner roller is supported by the wooden, and the outer roller by the iron arms to the outside roller is fastened a curved shaft, slate or binding, turned to end with a curve so a depth sufficient to admit the edge of the shaft, that is to be made with pipe just enough to form a chuck to one end of this roller, opposite a large cog wheel which matches to a small cog wheel, that is supported by, and fastened to, a shaft which shaft plays in iron clamps that are fastened to a bench, the end of the shaft is fitted a crank by which the machine is worked.

The iron arms are so fitted to the bench, that they may be extended or withdrawn, as occasion may require. The iron ^{arm} that supports the ends of the roller to which a wheel is fitted is jointed, that it may be removed of the guides in order to be from the roller the pipe when from the end of the roller is then supported by a seat projecting from the inner part of the bench. To this end of the roller at a distance from one end one half an inch from the end of the curved shaft plate is fitted a circular projection of iron one quarter of an inch which matches to a circular cavity in the inner roller made for that purpose.

End.
